TYPEWRITING MACHINE

George G. Going, Stamford, Conn., assignor to
Remington Typewriter Company, Ilion, N. Y.,
a corporation of New York

Application May 17, 1929. Serial No. 363,757

15 Claims. (Cl. 197—160)

My invention relates to typewriting and like machines and more particularly to ribbon feed and controlling mechanism and to means for automatically reversing the direction of the feed 5 of the ribbon.

The main object of my invention, generally stated, is to provide comparatively simple and highly efficient mechanism of the character specified.

10 Another object of my invention is to provide means for effecting an instantaneous reversal in the direction of the feed of the ribbon at and during a single stroke of a printing key, so that there is no period in the reversing operation when 15 the ribbon is not feeding in either one direction or the other.

A further object of the invention is to provide, simple, light and compact mechanism of the character specified that may be incorporated 20 in portable typewriting machines in which but little room is available for the embodiment of complicated weighty and bulky ribbon controlling, feed and reversing mechanism.

A still further object of my invention is to provide mechanism of the character specified with 25 the aid of which a reversal in the direction of the feed of the ribbon may be automatically effected with but little resistance offered to the operating parts.

30 To the above and other ends which will hereinafter appear, my invention consists in the features of construction, arrangements of parts and combinations of devices set forth in the following description and particularly pointed out 35 in the appended claims.

In the accompanying drawings, wherein like reference characters designate corresponding parts in the different views—

Fig. 1 is a fragmentary, substantially horizontal sectional view, with parts omitted, of a typewriting machine embodying my invention; the section being taken on the line 1—1 of Fig. 2 and looking in the direction of the arrows at said line.

45 Fig. 2 is an enlarged, detail, fragmentary, vertical fore and aft sectional view of a portion of the machine, the section being taken on the line 2—2 of Fig. 1, and looking in the direction of the arrows at said line.

50 Fig. 3 is an enlarged, detail, front elevation of the ribbon vibrator and some of the associated parts.

55 Fig. 4 is an enlarged, detail, fragmentary, top plan view showing a portion of the ribbon con-

trol, ribbon feed and automatic reversing means near one side of the machine.

Fig. 5 is a detail, perspective view of one of the connecting arms for the universal bar.

My invention is shown embodied, in the present instance, in a noiseless portable typewriting machine of the character disclosed in my application Serial #331,534, filed Jan. 10, 1929.

While the present invention is particularly available in such machine, and in portable machines generally, by reason of the compact character of mechanism of the invention, it should be understood that the construction may be included in other styles of typewriting and like machines, and may be employed in such machines generally, wherever found available.

The frame of the machine includes side plates 1 united by castings 2 and 3 and a comb plate 4. Printing key levers 5 are connected to printing instrumentalities, (not shown) preferably as indicated in my above mentioned application. Each of these key levers coacts with a metallic tongue 6 on an underlying universal bar 7. This bar extends from side-to-side of the machine in front of the comb plate 4 and is attached near its ends by screws 8 to foot pieces 9 of rearwardly extending bracket arms 10, preferably made of sheet metal. As shown in detail in Fig. 5 each bracket arm 10 has ears 11 formed integral therewith. These ears 11, and the cross piece 12 which 85 unites them, embrace a squared rock shaft 13 on three sides to rock therewith; the shank of a headed screw 14 passing through an opening 15 in the part 12 and engaging a tapped opening 80 in the shaft 13 to secure the companion bracket 90 arm in place. This forms a firm connection between the universal bar 7 and rock shaft 13 and enables the parts to be readily assembled and connected.

The rock shaft 13 is mounted at its ends on 95 pivot screws 16 received in tapped openings in the side plates 1 of the frame. This rock shaft carries a second pair of up-standing crank arms 17 that are connected thereto in the same manner as the arms 10. Thus, each arm 17 has lugs 100 18 that embrace the rock shaft on opposite sides to rock therewith and a single screw 19 secures the crank arm to the shaft.

The upper free end of each crank arm 17 carries a headed, shouldered, pivot screw on which is 105 pivoted the forward end of a sheet metal link 20 having at its rear end a portion 21 turned in a plane at right angles to the body portion of the link. This rear end portion of each link 20 is pivoted at 22 to the inwardly extending arm 23 110.

of an operating or ribbon feed device in the nature of an angular or bell crank lever 24. Each of these levers 24 is pivoted, as at 25, on a reversing or switching member 26 in the nature of a flat curved bar or yoke that extends from side-to-side of the machine in front of the system of type bars (not shown) and is mounted for longitudinal or endwise movement transversely of the machine, as will be hereinafter more fully explained.

Each lever 24 has a rearwardly extending arm 27 that during the normal operation of the parts is adapted to vibrate past the axis of its associated ribbon spool at each operation of a printing key lever, as will be understood from an inspection of Fig. 1. The arm 27 of each of these levers has pivoted thereto, at 28, a ribbon feed pawl 29 that extends inwardly from its associated arm and at its engaging end 30 is adapted to coat with the companion ratchet wheel 31 when permitted to do so, as determined by the position of the reversing bar 26.

A second or holding pawl 32 cooperates with each ratchet wheel 31 and is pivoted on the same pivotal center 25 as the companion operating lever 24. Due to this arrangement neither of the holding pawls 32 will be vibrated during the actuation of the levers 24, the active holding pawl 32 remaining in engagement with its ratchet wheel to prevent a backward movement thereof while the companion active feed pawl 29 is vibrated forward and back to advance the associated ratchet wheel and effect a feed of the ribbon. A coiled contractile spring 33 is connected at one end to a perforated ear 34 on a holding pawl, the opposite end of said spring being connected to a perforated lug 35 on the tail of the companion feed pawl 29. The force of each spring 33 tends to force the engaging ends of both its pawls 29 and 32 into engagement with the companion ratchet wheel. It will be understood of course that a spring 33 connects the pawls 29 and 32 at each side of the machine.

It is necessary, however, to limit the extent of motion of each pair of pawls 29 and 32 under the action of its spring 33 when such pawls are thrown out of engagement with the companion ratchet wheel by a longitudinal shifting of the reversing bar 26. This is accomplished by a stop pin 36 that extends up from the reversing bar near each end thereof into the path of the companion feed pawl 29 when the latter is in the release position, as shown at the right hand side of Fig. 1. The active pawl 29 does not reach the stop pin 36 as long as such pawl remains effective. When, however, the reversing bar 26 is shifted, say, from right to left and the parts are shown as they are positioned in Fig. 1, then the right-hand pin 36 will become effective to coat with the right-hand pawl 29 and prevent its spring 33 from forcing it into engagement with the companion ratchet wheel 31. At this time the companion holding pawl 32 will bear against the back of the associated feed pawl 29, thereby also preventing the companion holding pawl from engaging its ratchet wheel under the action of its spring 33.

Each of the ratchet wheels 31 has a hub 37 secured by a set screw 38 to a hollow shaft 39 supported in an elongated bushing or bearing member 40 provided with a circumferential supporting flange 41, said bushing being received and supported in an opening in the casting 3. The hub 37 coacts with the lower end of the bearing member 40 and prevents an upward displacement

of the hollow shaft 39 and ratchet 31, whereas, a flanged collar 42 of the ribbon spool is connected with a drive fit to the hollow shaft 39 and supports said shaft and the ratchet wheel thereon on the flange 41.

80

The construction of the ribbon spools and the controlling devices 45 carried thereby are practically the same as the corresponding devices employed in the No. 6 Remington-Noiseless machine and is disclosed in my Patent No. 1,665,736 dated April 10th, 1928. In such construction the only part of the spool that is removable is the upper flange 43 and the finger piece 44 riveted thereto. The controlling member 45 is pivoted at 46 to an ear 47 integral with a spool core 48 which in turn is riveted at its lower edge to the lower spool flange 49 which is fixed to the collar 42.

85

The controlling member 45 of each spool is in the nature of an angular or bell crank lever, one arm 50 of which has a hook at one end, said arm extending into the hollow shaft 39 through a vertical slot 39^a therein and supports a weighted member or rod 51. In accordance with my present invention this member 51 constitutes an interponent, arresting device or reversing member that is movable by gravity from the ineffective full line position shown in Fig. 2, to the effective position shown in dotted lines in said figure. In this last mentioned position of the member 51 it is in the path of movement 105 of the arm 27 of the companion actuating lever 24 for purposes which will presently appear. The other arm 52 of each controlling member 45 extends through a vertical slot 53 in the core 48 of the ribbon spool and is pressed against the 110 innermost layer of the ribbon 54 by the weight of the member 51. When the ribbon is fully unwound from the core 48, to which an end of the ribbon is attached, pressure of the ribbon on the arm 52 of the associated controlling member 115 45 is released, thereby permitting the companion interponent 51 to drop and to interpose its lower end in the path of operating movement of the 120 arm 27 of the associated lever 24.

90

As a printing key is depressed both lever arms 120 27 will be moved inward, but only one interponent 51, that on the exhausted spool, can be located in the path of its associated arm 27. The effective interponent 51 will coat with its associated arm 27 to arrest it and its lever 24 125 against pivotal movement but the continued depression of the printing key will cause the reactive force of said arrested lever 24 to be exerted outwardly against its pivot 25 and thus effect a longitudinal shifting movement of the 130 reversing bar 26. The effect of thus shifting the bar 26 is to carry both sets of pawls 29 and 32 with it, one set of pawls (that on the side of the machine upon which the interponent has functioned) being moved into engagement with 135 the companion ratchet wheel while the other set of pawls is moved out of engagement with the associated ratchet wheel.

100

Otherwise expressed, in the ordinary actuation of the operating levers 24 they turn to their full 140 extent on their pivots 25. When, however, one of said levers, which constitute part of the ribbon feed or actuating means, coacts with its companion interponent 51, this latter element acts as a resisting or arresting device for its 145 companion lever 24, so that further pressure from the key exerted thereon to turn it, reacts against its pivot 25 and the reversing bar 26 by which said levers 24 are carried thereby transferring the key pressure to shift said bar. This 150

may be best understood from a consideration of Fig. 4. This figure shows the parts at the right-hand side of the machine as they are disposed at the end of the depression of a printing key and at the completion of the shifting movement of the reversing bar 26 to the right, the key being held in the depressed position. This movement of the parts in question is brought about by a single depression of a key and they are moved from the position shown at the right-hand side of Fig. 1 to the position indicated in Fig. 4. The effect of this is to throw left-hand pawls 29 and 32 out of engagement with their ratchet wheel 31 and bring about an engagement of the corresponding right-hand pawls with their ratchet wheel, thus winding the ribbon on the exhausted right-hand ribbon spool instead of the left-hand spool, as was the case before the shifting of the bar 26, as above described, took place. The action of the parts is automatically reversed when the left-hand spool is exhausted.

It will be seen that each of the arms 27, where it passes beneath its companion interponent 51 in the ordinary feed movement of the companion lever 24, is provided with an outwardly extending enlargement or tail piece 27^a. The object of this tail piece is to prevent the companion interponent 51 from dropping behind instead of in front of the arm 27. In the event that the interponent 51 should be dropped when the arm 27 is at the end of its operating movement, then said interponent will drop on the tail piece 27^a and be sustained thereon until said arm returns to normal position, when the interponent will drop in front of the arm 27 ready to coact therewith at the next operation of said arm.

In order to properly guide each interponent 51 in its movement, I provide a bushing 55 secured with a drive fit in the lower end of each hollow shaft 39, as shown in Fig. 2. The bore of this bushing receives the lower end portion of the companion interponent 51 and guides it in its movement into and out of effective position.

A contractile spring 56 (Figs. 1 and 2) is connected at one end to a bracket 56^a secured by a screw 58 to the casting 3. The other end of this spring is connected to an upstanding arm 59 secured to the rock shaft 13. The force of this spring is exerted to effect an anti-clockwise movement of the rock shaft 13, as the parts are viewed in Fig. 2, and to return the feed pawls 29 and the other parts connected with said rock shaft to normal position. It will be understood therefore that the actual feed movement of the active ratchet wheel 31, and therefore of the ribbon connected therewith, is brought about by the returning spring 56, and during the return of the active feed pawl 29. It follows that a feed of the ribbon will be effected during an upstroke of a printing key after a reversal in the direction of feed of the ribbon has been effected by a shifting of the reversing bar during and by the down stroke of the same key.

From what has been said it will be understood that there is never a printing stroke effected without producing a feed of the ribbon in either one direction or the other, and that types may never hit in immediate succession on the same spot on the ribbon, which is a highly important factor in automatic ribbon reversing mechanism. In some ribbon reversing mechanisms it requires

as many as eight or nine printing operations before a reversal in the direction of the feed is effected, the types in the meantime striking at or about the same spot on the ribbon, which results in uneven imprints and injury to the ribbon, to the extent of punching holes in it in some cases. 80

The reversing bar 26 may be mounted for shifting movement in any suitable manner. In the present instance I have provided an integral upstanding ear 57 on the right-hand end thereof. To this ear is secured by a screw and nut connection 58 and 59 a shouldered pin 60 that receives a bearing in an opening in the right-hand side plate 1 of the frame. The pin 60 not only constitutes a sliding support for the right-hand end of the bar, but may be used as a finger piece by which the bar may be shifted by hand to the left to reverse the direction of the feed of the ribbon. 85 90 95

Two corresponding pins 61 and 62 are secured in a like manner to upstanding ears 63 and 64 at the left-hand end of the reversing bar 26. These pins slide in bearing openings in the left-hand side plate of the frame and project beyond said plate to provide finger pieces by which the reversing bar may be shifted to the right by hand, when desired. Interposed between each of the ears 57, 63 and 64 and the side plates 1 of the machine is a washer or contact face 65 of fiber, paper or some such suitable material on said ears, so as to reduce or eliminate any noise that might otherwise be produced by arresting the movements of the reversing bar in opposite directions. 100 105 110

In order that there may be an assurance of a complete shifting of the reversing bar 26 in either direction, and in order that the shifting bar may be held against accidental displacement from the position to which it has been shifted, I employ a C-shaped shiftable detent spring 66, shown in dotted lines in Fig. 1. This spring at one end is looped around a fixed pin 67 projecting up from the upper face of the casting 2 and at its other end the spring is looped around a pin 68 that projects down from the bottom side of the reversing bar 26. As the parts are shown in Fig. 1, the force of this spring is directed to maintain the reversing bar at the left-hand limit of its movement. When the reversing bar 26 is shifted to the right and the pin 68 passes the dead center position, or the position where the pin 68 is in alignment fore and aft of the machine with the pin 67, then the force of said spring will be exerted to move the reversing bar the remainder of the distance to the right and to hold said bar in the fully shifted position to the right. In other words the spring 66 constantly bears against the pin 68 and the effective force of the spring is directed to complete the movement of said pin and the bar 26 to which it is connected to right or left, depending on the position of the pin 68 to the right or left of the fixed pin 67. At the completion of such movement the effective force of the spring 66 tends to hold the parts in question against accidental displacement from the shifted position. 115 120 125 130 135 140

The rock shaft 13 in addition to actuating the ribbon feed and reversing means, is employed to actuate the ribbon vibrator at each printing operation. Thus, the upright arm 59, to which reference has previously been made, is secured by a screw 69 to the rock shaft 13 and has ears 70, such as those on the arms 10 and 17, which embrace the rock shaft on opposite sides thereof. A headed pivot pin 71 is extended through the arm 150

59 and provides a means for connecting the returning spring 56 to said arm 59. The pivot 71 also connects the forward end of an actuating pull link or member 72 to said arm 59 so that said 5 link may swing laterally relatively to said arm as well as to be given a movement fore and aft of the machine by said arm. The rear end of the link 72 is provided with an upwardly directed pin 73 that projects into a slot 74 in the inwardly directed arm 75 of a horizontally disposed angular or bell crank lever pivoted, at 76, to the fixed casting 2. Intermediate the ends of the slot 74 is a lateral slot or recess 74^a in the front wall thereof, for purposes that will be presently explained. The rearwardly directed arm 77 of this lever 75, 77, is pivoted, at 78, to a link 79 that extends transversely of the machine from near the right-hand side thereof to a depending arm 80 of an angular or bell crank ribbon vibrating lever 81, 10 to which the link 79 is pivoted at 82. The angular or bell crank lever 81 is pivoted at 83 to a sheet metal bracket 84 secured by screws 85 to the carriage support 86, preferably mounted for case shifting movement. An inwardly directed arm 87 on the lever 81 is pivoted at 88 to a ribbon vibrator 89, through which the ribbon 54 is threaded as it passes from one ribbon spool to the other. The lever arm 87 is substantially horizontally disposed and carries a headed pin 90, the 15 shank of which passes through a guide slot 91 in the bracket 84. To an upright arm 92 on the bracket is pivoted, at 93, a guide arm or link 94 parallel with the arm 87 and pivoted at its inner end, at 95, to the ribbon vibrator 89. This provides for supporting the ribbon vibrator wholly 20 from one side thereof.

It will be understood that the carriage support 86 receives a vertical case shifting movement and that the ribbon vibrator and the inner end of the 25 link 79 will partake of this movement without affecting the train of connections between said link 79 and the universal bar 7 which are carried by a fixed portion of the machine.

In order to vary the extent of throw of the 30 ribbon vibrator and thus determine whether the upper or lower half of, say, a two color ribbon is to be brought to the printing point at each operation, and in order to silence the operation of the vibrator for mimeograph work, I provide 35 means for adjusting the pull link 72 laterally to any one of three positions and maintaining it against accidental lateral displacement from the position to which it is adjusted.

The above mentioned means comprises a horizontally disposed bell crank lever 96 pivoted at 96^a on the upper side of the casting 2. One arm of this lever carries a pin 97 that works in a slot 98 in the link 72. The other arm of the lever 96 is pivoted, at 99, to a flat link 100 that extends 40 fore and aft of the machine and at its forward end carries an upstanding ear 101 to which a lever 102 is pivoted at 103. The lever 102 is pivoted at 104 to the right-hand side plate 1 of the frame, and is provided at its upper end with 45 a finger piece 105 by which the lever and the parts controlled thereby may be shifted to three different positions. One of such positions is that represented in Fig. 2, in which an ear 106 on the lever 102 coats with the casting 3. With the lever 102 in this position the lever 96 will be 50 maintained in the position shown in Fig. 2, thereby giving the shortest extent of throw to the ribbon and bringing the upper half thereof to the printing point.

55 A second position of the lever 102 is one deter-

mined by swinging it on its pivot 104 until arrested by an ear 107 on said lever coating with pin 108 extending from and fixed to the right-hand side plate 1. In this position, the lever 102 will have shifted the link 72 laterally to bring the pin 73 thereon along the slot 74 to the opposite side of the recess 74^a and nearer the pivot 76 of the lever 75, 77. Each actuation of the link 72, by the operation of a printing key will, at this time, give a greater extent of movement to the lever 75, 77 and to the vibrator, bringing the lower portion of the ribbon to the printing point.

60 In order to bring the lever 102 to either end of its throw and retain it against accidental displacement therefrom, I employ a C-shaped spring detent 109 corresponding to the detent spring 66, hereinbefore described. This spring 109 is looped at one end around the pin 108 and at its opposite end is looped around a pin 110 carried by the lever 102. As the parts are set in Fig. 2, the spring 109 is exerting its force to hold the lever 102 in the position shown in said figure. When, however, the lever 102 is shifted from the position shown a distance sufficient to carry the pin 110 across the dead center position, or across a line extending through the centers of the parts 104 and 108, then the force of the spring 109 will be exerted to force the lever 102 to and hold it against the pin 108.

65 When the lever 102 is midway between the two extreme positions referred to above, the link 72 will be held in such position that the pin 73 thereon will register with the lateral slot or recess 74^a in the lever arm 75 and no motion will be 70 transmitted from the link 72 to the lever 75, 77 and the parts controlled thereby and the vibrator will remain at rest.

In order to hold the lever 102 in the intermediate position I have provided a detent pin 111 which extends through an opening in the right-hand side plate 1. This pin is rounded on its inner contact end where it extends slightly beyond the inner face of the side plate. This pin is attached at its outer end to the free end portion 112 of a leaf spring 112 attached to the outer side of the associated side plate 1 by a riveted end of the pin 108. The inner end of the detent pin 111 is adapted to be seated under spring pressure in a depression 113 in the outer face of the lever 102 120 when the latter is in the intermediate position referred to above, and hold the lever and the parts controlled thereby against accidental displacement. At this time the effective force of the spring 109 will be practically dead centered 125 as the pin 110 at such time will be substantially on a line between the centers of the parts 104 and 108.

130 It should be understood that the universal bar 7 operates only on the ribbon control mechanism, the carriage feed mechanism (not shown) being controlled by a separate universal bar 114 (Fig. 1) actuated by the type bars, as disclosed in my prior application hereinbefore referred to.

135 It will be observed that by the present invention I provide a comparatively simple mechanism which is light in weight, compact in its structure, highly efficient and dependable in use, is not liable to be injured or broken and in which there is never a time in the operation of the printing 140 keys when the ribbon is not feeding in either one direction or the other.

145 While I have shown and described with considerable detail one form of construction embodying my invention, it should be understood 150

- that various changes may be made therein, and parts thereof may be employed without others, without departing from my invention as it is defined in the accompanying claims.
5. What I claim as new and desire to secure by Letters Patent, is:—
1. In a ribbon feed and automatic reversing means, the combination of a ribbon reversing bar mounted for shifting movement to bring about a reversal in the direction of the feed of the ribbon, ribbon feed devices mounted on said reversing bar key controlled means for actuating said ribbon feed devices at each printing operation, and interponents movable into and out of the path of said ribbon feed devices and released by the ribbon to bring one or the other of said interponents into the path of movement of the associated ribbon feed device and through the reaction thereof on said reversing bar cause the latter to be shifted longitudinally.
  2. In a ribbon feed and automatic reversing means, the combination of a ribbon reversing bar mounted for longitudinal shifting movement to bring about a reversal in the direction of the feed of the ribbon, operating devices carried by said reversing bar and mounted for movement with and independently thereof, key controlled means for actuating said operating devices at each printing operation, a ribbon feed pawl actuated by each of said operating devices, and interponents each mounted for movement into and out of the path of its associated operating device and controlled by the ribbon in such movements, the reaction of one or the other of said operating devices on the reversing bar resulting in a shifting thereof to render one feed pawl effective and the other ineffective and thus reverse the direction of the feed of the ribbon.
  3. In a ribbon feed and automatic reversing means, the combination of a ribbon reversing bar mounted for longitudinal shifting movement to bring about a reversal in the direction of the feed of the ribbon, ribbon feed devices carried by and pivoted on said reversing bar, a universal bar actuated at each printing operation, operative connections between said universal bar and ribbon feed devices, interponents each movable into and out of the path of its associated ribbon feed device, the reaction of each ribbon feed device against the reversing bar when such device is arrested by its interponent resulting in effecting a shifting of said reversing bar, and means controlled by the ribbon for determining the effectiveness and ineffectiveness of said interponents.
  4. In a ribbon feed and automatic reversing means, the combination of a ribbon reversing bar mounted for longitudinal shifting movement to bring about a reversal in the direction of the feed of the ribbon, operating devices carried by and movable on said reversing bar, means for actuating said operating devices at each printing operation, a ribbon feed pawl mounted on each of said operating devices and actuated thereby, a ratchet wheel actuated by each of said pawls, a ribbon spool turned intermittently by each of said ratchet wheels, interponents one associated with each of said operating devices to arrest its feed movement and movable into and out of the path thereof, the reaction of one or the other of the operating devices on the reversing bar effecting a shifting movement of said bar, and ribbon controlled means for controlling said interponents.
  5. In a key actuated ribbon feed and automatic reversing means, the combination of a ribbon
- reversing bar mounted for shifting movement to bring about a reversal in the direction of the feed of the ribbon, two ribbon spools, operating devices one for each ribbon spool actuated at each printing operation, one of said operating devices being effective to feed the ribbon when the other is ineffective depending on the longitudinal position of said reversing bar, means controlled by the key depression for actuating said operating devices, and means controlled by the ribbon for arresting either of said operating devices and causing the reaction of its operating movement under a key depression to be exerted against said reversing bar to shift it longitudinally.
6. In a ribbon feed and automatic reversing means, the combination of a ribbon reversing bar mounted for shifting movement to bring about a reversal in the direction of the feed of the ribbon, a pair of actuating levers carried by and pivoted on said reversing bar, means for actuating said levers at each printing operation, a pair of ribbon feed pawls actuated by said levers, a pair of ratchet wheels with which said pawls coat, the position of said reversing bar determining which pawl engages its ratchet wheel, and ribbon controlled arresting devices cooperative with said levers to arrest the pivotal movement thereof and cause the reactive force thereof to exert itself on the reversing bar to shift it.
7. A ribbon reversing mechanism for typewriting and like machines comprising a switching member the position of which determines direction of the feed of the ribbon, a ribbon feeding device pivoted on said switching member, key actuated means for operating said feeding device at each printing operation, and an automatically actuated arresting device adapted to be interposed in the path of and arrest said feeding device and cause the reactive force of its operating movement to be exerted on said switching member to switch it.
8. A ribbon reversing mechanism for typewriting and like machines comprising a switching member the position of which determines direction of the feed of the ribbon, a pair of ribbon feeding devices pivoted on said switching member, key actuated means for operating both of said feeding devices at each printing operation, and a pair of automatically actuated arresting devices each associated with one of said feeding devices and effective to arrest it and cause the reactive force of its operating movement to be exerted on the switching member to shift it in one direction or the other depending on which arresting device is effective.
9. A ribbon reversing mechanism for typewriting and like machines comprising a switching member the position of which determines direction of the feed of the ribbon, a pair of ribbon feeding devices pivoted on said switching member, key actuated means for operating both of said feeding devices at each printing operation, a pair of automatically actuated arresting devices each associated with one of said feeding devices and effective to arrest it and cause the reactive force of its operating movement to be exerted on the switching member to shift it in one direction or the other depending on which arresting device is effective, a pair of ribbon spools on which the ribbon is wound, and a pair of controlling devices one associated with each spool and by which said arresting devices are controlled, the layers of ribbon on the spools through

said controlling devices maintaining the arresting devices ineffective and permitting one or the other of said arresting devices to become effective as the ribbon releases one or the other of the controlling devices.

5 10. A ribbon reversing mechanism for type-writing and like machines comprising a switching member the position of which determines direction of the feed of the ribbon, a ribbon feeding device pivoted on and supported by said switching member, key actuated means for operating said ribbon feeding device by each depression of a key, a ribbon feed pawl actuated by said feeding device, a ratchet wheel actuated by said pawl, a ribbon spool turned by said ratchet wheel, an arresting device movable into and out of the path of said feeding device and when coacting therewith causing the reactive force of the operating movement of said feeding device to shift 15 said switching member and means controlled by the ribbon for controlling the movement of said arresting device into and out of the path of said feeding device.

10 11. A ribbon reversing mechanism for type-writing and like machines comprising a switching member the position of which determines direction of the feed of the ribbon, and automatically operating means for shifting said switching member in one direction or the other, said means including key actuated means for feeding the ribbon at each printing operation, and means for arresting a part of said key actuated feeding means and transferring the pressure exerted thereon to shift said switching member 15 after such arrest is effected.

15 12. A ribbon reversing mechanism for type-writing and like machines comprising a switching member the position of which determines direction of the feed of the ribbon, and automatically operating means for shifting said switching member in one direction or the other, said means including key actuated means for feeding the ribbon at each printing operation, and means for arresting a part of said key actuated feeding means and transferring the pressure exerted thereon to shift said switching member, and automatically operating means controlled by the ribbon for controlling said arresting means.

20 13. A ribbon reversing mechanism for type-writing and like machines comprising a switching member the position of which determines direction of the feed of the ribbon, and automatically operating means for shifting said switching member in one direction or the other, said means including key actuated means for feeding the ribbon at each printing operation, and means for arresting a part of said key actuated feeding means and transferring the pressure exerted thereon to shift said switching member.

25 30 35 40 45 50 55 60 65 70 75 80 85 90 95 100 105 110 115 120 125 130 135 140 145 150

cally operating means for shifting said switching member in one direction or the other, said means including a key actuated pivoted ribbon feed device that is given a pivotal movement by a key depression at each printing operation, and automatically operating means for arresting the pivotal movement of said feed device and exerting the reactive force thereof on said switching member to shift it.

14. A ribbon reversing mechanism for type-writing and like machines comprising a switching member the position of which determines direction of the feed of the ribbon, and automatically operating means for shifting said switching member in one direction or the other, said means including a pair of pivoted ribbon feed devices one for each ribbon spool, said devices being operatively connected with said switching member, key actuated means for operating said devices at each printing operation, a pair of arresting devices one associated with each of said ribbon feed devices and cooperative therewith to arrest its pivotal ribbon feed movement and cause its reactive force to be exerted on said switching member to shift it, and means controlled by the ribbon for controlling the movement of said arresting devices into and out of cooperative relation with ribbon feed devices.

14. In ribbon feed and automatic reversing mechanism, the combination of a pair of ribbon spools, a pair of ratchet wheels one for each ribbon spool, a reversing bar mounted for longitudinal shifting movement to bring about a reversal in the direction of the feed of the ribbon, operating levers carried by and pivoted on said bar, feed pawls carried by said levers, one of said pawls coacting with each of said ratchet wheels, a key actuated universal bar, connections from said universal bar to said levers, a pair of arresting members movable into and out of the paths of pivotal movement of said levers, each of said arresting members coacting with its associated lever to arrest its pivotal operating movement and through the reactive force of the lever on said reversing bar shift the latter longitudinally in one direction or the other depending on which of said arresting members is in the path of its associated lever, and means controlled by the ribbon coiled on the ribbon spools for controlling said arresting members.

GEORGE G. GOING.
